UNITED STATES PATENT OFFICE

ALEXANDER REID, OF VIRGINIA, MINNESOTA

WINDOW-CURTAIN-DISPLAY APPARATUS

Application filed April 17, 1939. Serial No. 355,774.

The present invention relates to an apparatus for displaying window curtains in stores and the like and has for its prime object to provide a frame revolvably mounted 5 on a wheeled base.

Another very important object of the invention resides in the provision of a means for revolvably mounting the frame on the base so as to prevent sagging and yet allow 10 the frame to be revolved with great ease.

A still further very important object of the invention resides in the provision of an apparatus of this nature which is exceedingly simple in its construction, inexpensive 15 to manufacture, strong and durable, thoroughly efficient and reliable in use and operation, and otherwise well adapted to the purpose for which it is designed.

With the above and numerous other objects in view as will appear as the description proceeds, the invention resides in certain novel features of construction and in the combination and arrangement of parts as will be hereinafter more fully described and 20 claimed.

In the drawings:

Figure 1 is an elevation of the apparatus embodying the features of my invention.

Figure 2 is another elevation thereof taken 30 at right angles to that shown in Figure 1, and

Figure 3 is an enlarged detail section taken substantially on the line 3—3 of Figure 1.

Referring to the details of the drawings, it will be seen that the numeral 5 denotes a 35 rectangular frame having a longitudinal dimension disposed vertically and provided on both edges thereof with spacing boards 6 to simulate a window frame from both sides and the top spacing boards have curtain brackets 7 mounted thereon so that the curtains 8 may be draped in the usual well known manner for display purposes.

A cross bar 9 is mounted in the frame intermediate the upper and lower ends thereof 45 and a longitudinal vertical bar 10 extends from the top to the bottom of the frame through the center of the cross bar 9. The wheeled base structure comprises a pair of spaced co-extensive parallel bars 11, mounted at their ends on casters 12, and a cross bar

14 is supported between the central portions of the bars 11. A plate 15 is secured to the bottom of the frame 5 to engage a similar plate 16 fixed to the top of the bar 14. A rod 17 extends through the center of the bar 55 14 through the surface of the plates 15 and 16 and then up through the bottom of the frame 5 and up through the vertical bar 10 a distance past the cross bar 9.

A plate 18 is threaded on the lower extremity of the rod 17 and is secured to the bottom of the base cross bar 14. Thus it will be seen that this rod prevents sagging of the frame but allows the frame to be easily revolved 60 on the wheeled base structure.

It is thought that the construction, utility and advantages of this invention will now be quite apparent to those skilled in this art, without a more detailed description thereof.

The present embodiment of the invention 70 has been disclosed in considerable detail merely for the purposes of exemplification, since in actual practice it attains the features of advantage enumerated as desirable in the statement of the invention and the 75 above description.

It is apparent that changes in the details of construction and in the combination and arrangement of parts may be resorted to, 80 without departing from the spirit or scope of the invention as hereinafter claimed or sacrificing any of its advantages.

Having thus described my invention, what I claim as new is:

1. An apparatus of the class described comprising a base including a pair of spaced 85 parallel coextensive bars, casters fixed to and supporting the extremities of the bars, a cross bar between the surface of the first mentioned bars, and a frame, and means for revolvably mounting the frame on the last mentioned bar, said frame having a vertical bar 90 therein, said means for revolvably mounting the frame comprising a rod extending through the cross bar of the base, through the bottom of the frame, and through the major portion of the vertical bar.

2. An apparatus of the class described comprising a base including a pair of spaced 95 parallel coextensive bars, casters fixed to and 100

- supporting the extremities of the bars, a cross bar between the surface of the first mentioned bars, and a frame, and means for revolubly mounting the frame on the last mentioned bar, said frame having a vertical bar therein, said means for revolubly mounting the frame comprising a rod extending through the cross bar of the base, through the bottom of the frame, and through the major portion of the vertical bar, a plate fixed at the bottom of the frame, and a plate fixed to the top of the cross base bar and a rod extending through said plate.
3. An apparatus of the class described comprising a base including a pair of spaced parallel coextensive bars, casters fixed to and supporting the extremities of the bars, a cross bar between the surface of the first mentioned bars, and a frame, and means for revolubly mounting the frame on the last mentioned bar, said frame having a vertical bar therein, said means for revolubly mounting the frame comprising a rod extending through the cross bar of the base, through the bottom of the frame, and through the major portion of the vertical bar, a plate fixed at the bottom of the frame, and a plate fixed to the top of the cross base bar and the rod extending through said plate, a plate threadedly engaged on the bottom extremity of the rod and fixed to the base cross bar.
4. An apparatus of the class described comprising a base including a pair of spaced parallel coextensive bars, casters fixed to and supporting the extremities of the bars, a cross bar between the surface of the first mentioned bars, and a frame, and means for revolubly mounting the frame on the last mentioned bar, said frame having a vertical bar therein, said means for revolubly mounting the frame comprising a rod extending through the cross bar of the base, through the bottom of the frame, and through the major portion of the vertical bar, a plate fixed at the bottom of the frame, and a plate fixed to the top of the cross base bar and the rod extending through said plate, a plate threadedly engaged on the bottom extremity of the rod and fixed to the base cross bar, said frame having window frame simulating casing members on both sides thereof and curtain hanging means mounted thereon.

55 In testimony whereof I affix my signature.
ALEXANDER REID.
